CLAIM

The ornamental design for a plastic bucket lid removal tool, as shown.

DESCRIPTION

FIG. 1 is an elevational view of a first side of the plastic bucket lid removal tool showing my new design;

FIG. 2 is a bottom plan view thereof;

FIG. 3 is a top plan view thereof;

FIG. 4 is an elevational view of a second side thereof;

FIG. 5 is a handle end elevation view thereof; and

FIG. 6 is a lid-grasping end elevational view thereof.

FIG. 3

FIG. 4

FIG. 5

FIG. 6
